United States Patent Office

Des. 183,875
Patented Nov. 11, 1958

183,875

NOVELTY HAT

Tony Cortese, Richmond, Calif.

Application June 28, 1957, Serial No. 46,771

Term of patent 14 years

(Cl. D3—13)

Fig. 1

The essential features of my design reside in the portions shown in solid lines on the drawing.

I claim:

The ornamental design for a novelty hat, substantially as shown and described.
